UNITED STATES PATENT OFFICE.

GEORGE O. POWELL, OF WYNNEWOOD, OKLAHOMA.

CHURN.

Application filed July 23, 1923. Serial No. 653,277.

To all whom it may concern:

Be it known that I, GEORGE O. POWELL, a citizen of the United States, residing at Wynnewood, in the county of Garvin and State of Oklahoma, have invented a new and useful Churn, of which the following is a specification:

The device forming the subject matter of this application is a churn of the general sort shown in my prior Patent No. 829,291 issued on August 21, 1906.

The invention proposes sundry improvements in the patented churn, one improvement being so to construct the churn that the milk will not rise through the openings in the base, as the plunger rods reciprocate, and accumulate on the standard. Another improvement relates to the means for securing the standard to the base.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in elevation, a device constructed in accordance with the invention; Figure 2 is an elevation wherein the device is viewed at right angles to the showing of Figure 1; Figure 3 is a fragmental vertical section; Figure 4 is a cross section on the line 4—4 of Figure 3; Figure 5 is a bottom plan showing the dashers; Figure 6 is a perspective view illustrating one of the attaching elements.

Since the device is an improvement on the churn shown in my Patent No. 829,291, the description in this application may be shortened accordingly, since many parts of the device hereinafter described are shown in the patent alluded to.

The numeral 1 marks a base adapted to be mounted on a churn body 2. A standard is shown at 3 and rests at its lower end on the base 1, the base having an upstanding dowel pin 4 engaged in the lower end of the standard 3. A pulley 5 is journaled

for rotation in the upper end of the standard 3, and it is proposed that the pulley 5 shall be a ball bearing pulley. Slides 6 are mounted for vertical reciprocation in the standard 3 and are equipped with outstanding handles 7. A flexible-element 8 is connected at its ends to the slides 6 and is trained across the pulley 5. The upper ends of dasher rods 9 are secured to the slides 6 and operate in openings 10 fashioned in the base 1. On the lower ends of the rods 9 dashers 11 are mounted.

An angular latch 12 is pivoted at 14 to one side of the standard 3 and includes a horizontal arm 15 having a slot 16 adapted to engage beneath a wing nut 17 on a stud 18 carried by the base 1. One of the improvements contemplated relates to the attachment of the standard to the base 1. In my prior patent, the standard is attached to the base through the instrumentality of a hook adapted to engage beneath a bar secured by a block on the base. It has been claimed by some, that the construction above described is defective in that it affords no adjustment. In order to remedy this difficulty recourse is had to an angle bracket 19, including a vertical flange 20 and a horizontal flange 21, the vertical flange 20 being attached by securing elements 22 to the standard 3 at the lower end of the standard. In the horizontal flange 21 there is an end slot 23 adapted to engage beneath the head 24 of an adjusting device, such as a screw 25 threaded into the base 1. It will be obvious that by rotating the screw 25, the same may be moved lengthwise, thereby enabling the head of the screw to cooperate properly with the slotted horizontal flange 21 of the angle bracket 19.

Another alleged defect which some have found in the patented churn above alluded to is that the dasher rods work so close to the standard 3 that, as the dasher rods reciprocate, the milk is carried upwardly through the holes in the base 1 and find lodgment on the standard 3. In order to remedy this shortcoming, hangers 26 are supplied, the lower ends 27 of the hangers being offset horizontally from the upper ends 28 of the hangers, the lower ends of the hangers being mounted in the dasher rods 29, and the upper ends of the hangers bearing against the outer surfaces of the slides 6, the upper ends 28 on the hangers having seats 29 adapted to be engaged beneath

wing nuts 30 carried by studs 31 on the slides 6. The result is that the dasher rods 9 are set outwardly, away from the standard 3 it being possible to locate the openings 10 entirely outside of the cross sectional contour of the standard 3. The rods 9, thus, are spaced from the standard 3, and, in the reciprocation of the rods 9, any milk which may be accidentally carried upwardly 10 through the openings 10 will not foul the standard 3. The standard, thus, is kept clean, and there is no lodgment of hardened milk in the guideway 32 wherein the slides 6 reciprocate.

15 What is claimed is:

1. In a device of the class described a base, a standard mounted on the base, a pulley carried by the standard, a flexible element trained across the pulley, rods connect- 20 ed to the flexible element and mounted for reciprocation in the standard, pressure rods slidable in the base and connected to the slides, an angular latch pivoted to one side of the standard, means on the base where- 25 with the latch engages, an angle bracket comprising horizontal and vertical arms, the vertical arm of the angle bracket being secured to the opposite side of the standard, the horizontal arm of the angle bracket hav- 30 ing a slot in its end, and a screw passing

through the slot and including a head engag- 35 ing the horizontal arm of the angle bracket, the screw being threaded for adjustment into the base.

2. In a device of the class described, a base, a standard carried by the base, a pulley journaled on the standard, a flexible ele- 40 ment trained across the pulley, guides mounted for reciprocation on the standard and connected to the flexible element, rods mounted for reciprocation in the base, the base having openings wherein the rods are 45 slidable dashers carried by the rods, hangers connected at their ends to the slides and to the rods, the upper and lower ends of the hangers being offset horizontally, thereby 50 to increase the space between the rods and the standard and to permit the openings to be located entirely outside of the cross sec- tional contour of the standard thus to pre- vent the milk which is carried upwardly by the rods from accumulating on the standard.

In testimony that I claim the foregoing as my own, I have hereto affixed my signature in the presence of two witnesses.

GEORGE O. POWELL.
